UNITED STATES PATENT OFFICE.

CHARLES P. KLOMER, OF PITTSBURGH, PENNSYLVANIA, ASSIGNOR OF ONE-HALF TO
LOUIS P. SIMON, OF PITTSBURGH, PENNSYLVANIA.

DOOR-SECURING DEVICE.

Application filed August 13, 1920. Serial No. 403,343.

To all whom it may concern:

Be it known that I, CHARLES P. KLOMER, a citizen of the United States, residing at Pittsburgh, in the county of Allegheny and 5 State of Pennsylvania, have invented new and useful Improvements in Door-Securing Devices, of which the following is a specification.

My invention pertains to door-securing devices, of the class which permit the door to be opened to a certain extent but prevent it from being opened further, and relates especially to that kind of device which includes a pivoted Z-shaped member the 15 shank or center part of which limits the possible movement of the door.

It is the principal object of my invention to provide a door-securing device which, while readily releasable from within, cannot be released from the outside by the application of any reasonable force or by the employment of any degree of skill. It is a further object of my invention to provide a door-securing device of the particular 25 kind specified above in which a hook portion has sliding engagement with a portion of the door so as to be pressed thereagainst from the inside of the door outwards when an attempt is made to open the door beyond 30 the limit of the device. It is another object of my invention to provide a door-securing device which can be simply and quickly changed from an operative to an inoperative position, as well as to produce one 35 which will be attractive in appearance and will not, in use, mar the surface of the surrounding woodwork. Other and further objects will appear from the following specification and the claims forming a part 40 thereof.

By way of example, I have described one form of door-securing device embodying my invention in the following specification and shown it in the accompanying drawing, in 45 which:

Fig. 1 is an elevation of a portion of a door frame and of the adjacent door, having a door-securing device constructed in accordance with my invention applied there- 50 to, the door being shown closed;

Fig. 2 is a section on the line 2—2 of Fig. 1, looking in the direction of the arrows; and

Fig. 3 is a section on the line 3—3 of Fig.

1, looking in the direction of the arrows, 55 the door being shown partly open.

Like reference characters refer to like parts throughout the following specification and the several figures of the drawing.

In the drawing, 10 indicates the door-jamb and 11 indicates the door. To the jamb 10 is secured a plate 12, this plate being let in flush and having a flange 13 extending at right angles into the door-opening and also let in flush. A boss 14 extends 60 outward from the plate 12 and has a hole therethrough formed with a small longitudinal slot 15 on the side adjacent the door-jamb.

The securing member comprises a shank 70 16, of a length dependent upon the extent to which it is desired that the door can be freely opened, having a portion thereof bent at right angles to form a hinge-pin 17, the latter being adapted to enter the hole of 75 14. The hinge-pin 17 is provided with a small stud 18, which stud can pass through the slot 15, to permit the hinge-pin to enter its hole, when the shank is held horizontal, but prevents the hinge-pin from 80 being withdrawn from its hole when the shank is in any other than a horizontal position. At its other end, the shank 16 is bent outwardly to form an engaging portion 19, 85 which portion forms somewhat less than a right angle with the shank, so as properly to accommodate itself with the face of the opening door. Upon the end of the engaging portion 19 is provided a rotatable 90 roller 20.

Upon the inside face of the door 11, extending inward from the door-edge and downward from the level of the plate 12, is secured a plate 21 formed with an 95 upstanding ridge 22 which approaches the door towards the top of the plate. The edge of the roller 20 bears against this ridge during the opening and closing of the door.

As the door is moved inward from its closed position, the roller 20 rides upward 100 on the plate 21 (Fig. 3) until the shank 16 reaches an approximately horizontal position, when, owing to the engagement of the roller against the plate 21, the door can be opened no further. It will be noted that 105 there is no practical way in which force can be applied to break the securing device, this being chiefly due to the fact that the secur-

ing member is pivoted on the jamb and engages outwards against the door. Were the securing device pivoted on the door instead of the jamb, some kind of bar would have to be provided to take the inward pressure of the securing member; and it would be a comparatively simple matter for a burglar, operating through the partly open door, to wrench such bar from its fastening. My 10 construction leaves no opportunity for anything of the sort, and at the same time involves nothing bulky in the way of heavy fastenings. In addition to this, the other features of construction are such that no 15 amount of skillful manipulation, as by means of cords, wires or the like, will enable the device to be released by a person operating from the outside of the door. The device, moreover, is simple and cheap 20 of manufacture, can be easily installed, and cannot, in use, mar in any way the wood-work of the door.

Having thus fully described my invention, what I claim as new, and desire to secure by 25 Letters Patent, is:

1. The combination with a door and a door jamb of a door securing device comprising an element secured to the door-jamb, and a securing member having a shank 30 hingedly connected with said element and having a portion extending at an angle from said shank in the path of the door so as to engage in an outward direction against said door when the latter is moved inwardly.

2. The combination with a door and a door jamb of a door securing device comprising an element secured to the door-jamb, and a securing member having a shank hingedly and separably connected with said 40 element and having a portion extending at an angle from said shank in the path of the door so as to engage in an outward direction against said door when the latter is moved inwardly.

3. The combination with a door and a door jamb of a door securing device comprising a socket secured to the door-jamb, and a securing member including a shank, a hinge-pin extending from said shank 50 and entering said socket, and an engaging portion extending at an angle from said shank in the path of the door so as to engage in an outward direction against said door when the latter is moved inwardly.

4. The combination with a door and a door jamb of a door securing device com-

prising an element secured to the door jamb; a securing member having a shank hingedly connected with said element, and having a portion extending at an angle in 60 the path of the door; and a plate for engagement by said securing-member-portion and adapted to be secured to the door.

5. A door securing device comprising an element for being secured to the door jamb; and a securing member comprising a shank hingedly connected with said element, a portion extending at an angle from said shank in the path of the door, and a door-engaging 65 roller on said portion.

6. A door securing device comprising an element for being secured to the door-jamb; a securing member comprising a shank hingedly connected with said element, a portion extending at an angle from said 75 shank in the path of the door, and a door-engaging roller on said portion; and a plate for engagement by the face of said roller, and having a ridge for engagement by the side of said roller.

7. A door securing device comprising a socket for being secured to the door jamb, and a securing member including a shank, a hinge pin extending from said shank and entering said socket, a portion extending at 85 an angle from said shank in the path of the door, and an anti-friction roller carried by said portion and adapted to engage in an outward direction against said door when the latter is moved inwardly.

8. A door securing device comprising an element for being secured to the door jamb; a securing member having a shank hingedly connected with said element, a portion extending at an angle in the path of the door, 95 an anti-friction roller on said portion; and a plate for engagement by said friction roller and adapted to be secured to the door.

9. A door securing device comprising an element for being secured to the door jamb, 100 a securing member having a shank and a portion extending at an angle from said shank in the path of the door so as to engage in an outward direction against said door when the latter is moved inwardly, and 105 means for hingedly connecting said shank with said element so as to be removable at one position of rotation.
